CAN FILLING MACHINE

Charles H. Ayars, Salem, N. J., assignor to Ayars Machine Company, Salem, N. J., a corporation of New Jersey

Application September 23, 1935, Serial No. 41,652

11 Claims. (Cl. 226—69)

This invention relates to can filling machinery and has particular reference to machinery for filling cans with juicy or semi-juicy material such, for instance, as tomatoes. In the tomato canning industry, tomatoes after being picked are usually washed mechanically and by some sort of a machine like that shown and described in my co-pending application Serial No. 752,954, filed November 14, 1934, from which machine they are passed on to a scalding and the skins removed. The tomatoes are then passed to a can filling machine where measured quantities are placed continuously in cans, the cans capped and then passed to a conditioning machine for cooking the same.

While the present invention will be discussed in connection with the filling of cans with tomatoes, it will, of course, be understood that other commodities such, for instance, as peaches and other fruits and vegetables, may be placed in cans by the mechanism described herein.

In machines for filling cans with tomatoes and in such machines as shown by my former United States Letters Patents No. 1,459,492, granted June 19, 1923; No. 1,476,278, granted December 4, 1923; No. 1,480,335, granted January 8, 1924; and No. 1,883,460, granted October 18, 1932, the hopper from which the commodity is received by the telescoping measuring cups is located directly above the rotating turrets so that when the measuring cup is opened to be filled from said hopper the entire weight of the contents of said hopper bears upon the material entering the cup and, in the case of tomatoes, this weight is sufficient to disrupt the whole tomatoes and break them into pieces.

The primary object of the present invention is to provide a machine whereby cans may be filled with fragile commodities such, for instance, as tomatoes with the skin removed, and wherein the tomato will not be disrupted or broken by the weight of the material in the hopper, so that whole tomatoes and the like may be directed into the cups for deposit in the cans.

Another object of the present invention is to provide such a machine in which the whole tomatoes will not be subject to the action of the shaker which is likely to disrupt the same.

Still another object of the invention is to provide such a machine wherein the whole tomatoes will be deposited into the cups prior to the deposit of the pulpy disrupted tomatoes, whereby the whole tomatoes will not be subject to the levelling action of the shaker.

Still another object of the invention is to pro-

vide such a machine with a hopper having means for straining the juice from the tomatoes placed in said hopper and directing the same into a well.

A still further object of the invention is to provide means in the said juice well or pan whereby measured quantities of the said juice is deposited into each of the cans prior to the reception of the tomatoes into the same.

Another object is to provide means in the said juice well or pan for maintaining a level of the said juice therein and means for carrying off the excess.

According to the invention, the can filling machine comprises upper and lower rotatable turrets with telescoping measuring cups thereon for adjusting the measuring capacity of said cups, a shaker or agitator on the upper turret and a hopper having its open upper end offset vertically from said turrets and having an angularly disposed funnel portion for directing tomatoes placed therein on to said upper turret. The funnel portion of said hopper is so arranged in angularity that the pulpy mass of broken or disrupted tomatoes will fall on to the turret at the point of entrance from said funnel portion, while the whole tomatoes will rise to the top of said pulpy mass and will roll across the turret and fall into the cups at the other side of the turret. The hopper may also be provided with perforations and a wall behind the same provided with means for draining the juice into a juice pan. The juice pan may also be provided with an adjustable measuring apparatus whereby a measured quantity of said juice is deposited into each of the cans.

The drawings illustrate an embodiment of the invention and the views therein are as follows:

Fig. 1 is a perspective view showing a filling machine with the novel mechanism incorporated therein.

Fig. 2 is a top plan view showing the relative positions of the hopper, turrets, agitator or shaker, and their connecting mechanism.

Fig. 3 is a vertical sectional view on the line 3—3 of Fig. 2, looking in the direction of the arrows.

Fig. 4 is a vertical sectional view taken on the line 4—4 of Fig. 2 and looking in the direction of the arrows, and

Fig. 5 is a vertical sectional view on the line 5—5 of Fig. 2, looking in the direction of the arrows.

The type of machine illustrated in Fig. 1 is substantially like that shown in the patents hereinbefore enumerated and having applied thereto

55

the several features of invention hereinbefore mentioned.

The machine is provided with a can receptacle 6 for feeding cans on to a screw 7 which feeds them into proper position to be received by a star wheel 8 which locates the said cans in position below the funnels 9. This can feeding and positioning mechanism is explained in my application Serial No. 385,243, filed August 12, 1928.

10 Above the funnels 9 is a drip pan 11 for the purpose of catching any juice which escapes during the filling operation and this drip pan is provided with a well 12 having measuring apparatus 13 therein, as later explained.

15 The machine is also provided with lower and upper turret members 14 and 16 which have upwardly and downwardly circular flanges 17 and 18 respectively, which said flanges telescope to provide adjustable measuring cups for measuring 20 predetermined quantities of materials to be placed in the cans A. These turrets are rotatable through the medium of the shaft 19 connected in any suitable manner to the horizontal main shaft of the machine driven by the pulley 21.

These turrets with their telescoping cups are clearly shown in United States Letters Patent No. 1,883,460, above referred to.

25 The drip pan 11 may be formed integral with the lower turret.

Above the turrets 14 and 16 is an agitator or shaker 22, which said member is provided with an opening 23 which provides a passageway for the material to enter the measuring cups. The 30 walls of this shaker are substantially vertical on one side, as shown at 24, and outwardly flared on the other side, as shown at 26, Fig. 4. This shaker member is pivotally mounted on the shaft 21 by the sleeve 28 on the extension 29.

40 An arm 31 diametrically opposite the extension 29 extends from the shaker and is provided at its outer end with a slot 32 in which operates a wrist pin 33 mounted on the disk 34, which disk is mounted upon the shaft 36 and adapted for 45 rotation therewith. The shaft 36 is in turn driven in any suitable manner, as from the main shaft of the machine.

This type of agitator or shaker is clearly described in my Patent No. 1,818,780, granted Au- 50 gust 11, 1931.

The shaker or agitator 22 is surmounted by hopper mechanism which in the design illustrated herein consists of an outwardly flaring part 37 with a funnel portion 38 and a vertical wall portion 39 extending around the shaker 22 and connecting the funnel portion 38 of said hopper.

The outwardly flared portion 37 is offset vertically from the turrets 14 and 16, and the funnel portion is set at such an angle as will direct the 60 pulpy broken tomatoes on to the upper turret at a point near where the shaker or agitator will direct such mass into the cups B formed by the flanges of said turrets, while the whole tomatoes will rise to the top of said pulpy mass and will 65 roll across the said upper turret and fall into the pockets on the other side of the turret.

Considering Fig. 2, the pulpy mass of tomatoes will be directed at a point near the cup nearest the center line of said machine and covered by 70 said hopper, while the whole tomatoes will roll across the turret and be deposited in the cups B' and B².

As the turrets are rotating in the direction of the arrow C, Fig. 2, the whole tomatoes will be 75 directed into the cups B' and B² prior to the

pulpy mass being deposited therein, so that as the pulpy mass which is filled into the cans and above the whole tomatoes comes into contact with the shaker or agitator 22, the whole tomatoes will not be disrupted as would be the case 5 if they extended above the top of the can, in which case the shaker or agitator would sever them in levelling the contents.

The funnel is provided with perforations 41 in the lower part of the same and a separate wall 42 will direct the juice passing through said perforations into the spout 43 formed on the bottom of the same. This spout directs the juices into the flaring cup 44 forming part of the drip or juice pan.

10 The juice pan has a rectangular extension 46 into which the pivoting shaft 27 of the shaker is screwed by threads 47 on the lower end thereof and this extension has a wall 48 forming overflow means for the said drip pan, and excess juices 20 which flow into said rectangular extension are carried therefrom through the opening 49 which may be connected with a pipe 51 extending to any means for collecting said excess.

15 The well 12 formed in the drip pan of the lower turret has a downwardly extending part 52 provided with a chamber 53 and with a pipe 54. A shaft 56 extends into said well and has affixed to its upper end a rotary member 57 which has a measuring chamber 58 formed in the lower face 30 of the same; and said member is provided with a sleeve 59 in which a capacity adjusting member 61 operates. This capacity adjusting member is adjusted by virtue of a screw-threaded pipe 62 and rotary hand member 63, so that the said 35 member 61 may be raised or lowered to alter the capacity of the measuring chamber 58. An air vent 62^a extends through the member 61 and communicates with the pipe 62.

20 It will readily be seen that when the shaft 56 40 which is connected by any suitable means to the main operating shaft rotates, the member 57 will rotate; and as the drip pan 11 contains the juices 45 of the material being filled into the cans, the chamber 53 will always be filled with said juice and as the chamber 58 passes over the chamber 53, the first named chamber will likewise be filled with juice, and said juice will be carried over to the pipe 54 and directed from said pipe into the open top of a can A, as shown in Fig. 1.

25 The machine is, of course, so timed that for each operation of the member 57 a can will have been advanced to a point beneath the pipe 54. In this way, each can receives a measured quantity of juice and consequently the cans are uniformly filled.

30 The hopper member is maintained in position by means of the extensions 66 and 67 extending out from the vertical wall 39 fitting over shafts 27 and 68 respectively.

35 It will be seen that in a machine of the type described, the whole tomatoes can be placed in the cans without fear of disruption and the pulpy mass placed in around the same to fill the voids and the excess levelled off by means of the shaker. 65

40 It will also be seen that by the juice straining means cooperating with the juice measuring and filling means, an accurate amount of juice may be placed in each can and, therefore, the cans will be uniformly filled with a certain percentage of 70 whole tomatoes, tomato pulp and juice.

45 Of course the mechanism illustrated and described herein may be modified in various ways without departing from the invention herein set forth and hereafter claimed.

The invention is hereby claimed as follows:

1. In a can filling machine comprising upper and lower horizontally disposed rotatable turrets with telescoping measuring cups thereon, a hopper having its open upper end offset vertically from said turrets and having an angularly disposed funnel portion for directing material placed therein onto said upper turret, said funnel being so disposed that substantially spherical objects will roll across the turret and enter the cups opposite the base of the funnel while pulpy matter will fill into said cups at the mouth of the funnel.
2. In a can filling machine comprising upper and lower horizontally disposed rotatable turrets with telescoping measuring cups thereon, a hopper having its open upper end offset vertically from said turrets and having an angularly disposed funnel portion for directing material placed therein onto said upper turret, and means for preventing said material from passing over the edge of said turret, said funnel being so disposed that substantially spherical objects will roll across the turret and enter the cups opposite the base of the funnel while pulpy matter will fill into said cups at the mouth of the funnel.
3. In a can filling machine comprising upper and lower horizontally disposed rotatable turrets with telescoping measuring cups thereon, a hopper having its open upper end offset vertically from said turrets and having an angularly disposed funnel portion for directing material placed therein onto said upper turret, and means connecting the open end of said funnel for preventing said material from passing over the edge of said turret, said funnel being so disposed that substantially spherical objects will roll across the turret and enter the cups opposite the base of the funnel while pulpy matter will fill into said cups at the mouth of the funnel.
4. In a can filling machine comprising upper and lower horizontally disposed rotatable turrets with telescoping measuring cups thereon, a hopper having its open upper end offset vertically from said turrets and having an angularly disposed funnel portion for directing material placed therein onto said upper turret, and a vertical wall connecting the open end of said funnel for preventing said material from passing over the edge of said turret, said funnel being so disposed that substantially spherical objects will roll across the turret and enter the cups opposite the base of the funnel while pulpy matter will fill into said cups at the mouth of the funnel.
5. In a machine for filling cans with juicy material, comprising adjustable measuring cups and an agitator for shaking pulpy material into said cups for deposit in the cans, a juice pan around the cups, a hopper having means for straining the juice and directing same into said pan, and means in said pan operated by said machine for supplying cans with measured quantities of said juice.

6. In a machine for filling cans with juicy material, comprising adjustable measuring cups and an agitator for shaking pulpy material into said cups for deposit in the cans, a juice pan around the cups, a hopper having means for straining the juice and directing same into said pan, and a rotatable measuring device in said pan for supplying cans with measured quantities of said juice.

7. In a machine for filling cans with juicy material, comprising adjustable measuring cups and an agitator for shaking pulpy material into said cups for deposit in the cans, a juice pan around the cups, a hopper having means for straining the juice and directing same into said pan, and a rotatable and capacity adjustable device in said pan for supplying cans with measured quantities of said juice.

8. In a machine for filling cans with juicy material, comprising adjustable measuring cups and an agitator for shaking pulpy material into said cups for deposit in the cans, a juice pan around the cups, a hopper having perforations in the wall thereof leading into means for collecting the juice and directing same into said pan, and means in said pan for supplying cans with measured quantities of said juice.

9. In a machine for filling cans with juicy material, comprising adjustable measuring cups and an agitator for shaking pulpy material into said cups for deposit in the cans, a juice pan around the cups, a hopper having perforations in the wall thereof leading into means for collecting the juice and directing same into said pan, means in said pan for supplying cans with measured quantities of said juice, and overflow means on said pan for carrying off excess juice.

10. In a can filling machine for tomatoes comprising upper rotatable turrets with telescoping measuring cups thereon, a hopper having its open upper end offset vertically from said turrets and having a funnel portion so disposed in angularity that the pulpy disrupted tomatoes will fall onto the upper turret at the point of entrance from said funnel while whole tomatoes will rise from the pulpy mass and roll across said upper turret and fall into said cups substantially opposite said entrance point.

11. In a can filling machine for juicy materials, comprising upper and lower rotatable turrets with telescoping measuring cups thereon, a juice pan, a hopper having its open upper end offset vertically from said turret and having a funnel portion extending in a downward angular direction, said hopper having perforations and means for directing the juice of said material into the juice pan, means for serving a measured quantity of said juice into each can to be filled, and overflow means for removing excess juice from said pan.

CHARLES H. AYARS. 60
